UNITED STATES PATENT OFFICE.

GEORGE B. BLILEY, OF RICHMOND, VIRGINIA.

TOY.

1,274,979.

Specification of Letters Patent.

Patented Aug. 6, 1918.

Application filed August 10, 1917. Serial No. 185,573.

To all whom it may concern:

Be it known that I, GEORGE B. BLILEY, a citizen of the United States, residing at Richmond, in the county of Henrico and 5 State of Virginia, have invented new and useful Improvements in Toys, of which the following is a specification.

This invention is an improved toy adapted for keeping a series of small balls such 10 as marbles in motion and embodying a motor driven elevator, a spirally arranged run-way to which the marbles are successively supplied by the elevator, a drop column to which the marbles roll on the said run-way 15 and a return run-way which conveys the marbles by gravity from the bottom of the drop column to the elevator so that the elevator is successively supplied with marbles to be carried thereby to the spiral run-way, 20 the object of the invention being to provide an improved toy of this character which is simple in construction and which operates efficiently.

The invention consists in the construction, 25 combination and arrangement of devices hereinafter described and claimed.

In the accompanying drawings:-

Figure 1 is a side elevation of a toy constructed and arranged in accordance with 30 my invention.

Fig. 2 is a similar view at right-angles to Fig. 1 and omitting the motor, the motor shaft being shown in section.

Fig. 3 is a plan of the same.

Fig. 4 is a vertical transverse sectional view of the same on the plane indicated by the line 4—4 of Fig. 3.

In the embodiment of my invention here shown a base 1 is provided from which rises 40 a hollow column 2 at the upper end of which column is a circular disk or table 3 which is provided with a spiral run-way 4, the intake end of the run-way being at one side of the disk or table as at 5 and the opposite 45 end of the run-way being at the center of the plate or table as at 6 and corresponding with the upper end of the hollow column 2. A member 7 is arranged on the base and is provided on its upper side with a gravity 50 acting run-way 8 the upper end of which communicates through an opening 9 with the bottom of the bore in the drop column 2 so that a marble or other like device which

drops through the column from the inner end of the run-way 4 is caused to pass 55 through the opening 9 and enter the run-way 8, said run-way 8 carrying the ball to the outer end of the member 7 by gravity and causing the ball to be fed to a pocket 10 of an endless elevator 11. 60

Said endless elevator is here shown as a belt and the pockets 10 thereof are suitably spaced and each, on the upwardly moving side or lead of the elevator being open at the upper side. 65

An upper roller 12 is mounted on a suitable stub shaft 13 which is carried by a post 14, said post extending from the base to the plate or table 3. A lower roller 15, which engages the lower bight of the endless 70 elevator is arranged on a shaft 16 of a spring motor 17, the winding key of which is shown at 18. A suitable number of marbles or other spherical objects is provided, said marbles being indicated at 19. 75

The operation of the toy is as follows: When the spring motor has been wound and started the elevator is set in motion and one lead thereof is caused to move upwardly as indicated by the arrow. A suitable number 80 of the marbles are used and they are first, one at a time, dropped through the column 6 and caused to pass successively over the run-way 8 and to be successively supplied by their own gravity to the pockets of the elevator. As each pocket of the elevator passes over the upper roller 12 the marble drops 85 therefrom into the intake end of the spiral run-way 4. The marbles roll on said run-way and drop through the opening 6 and 90 hence are kept constantly in motion as long as the motor operates.

While I have herein shown and described a preferred form of my invention, I would have it understood that changes may be 95 made in the form, proportion and construction of the several parts, without departing from the spirit of my invention and within the scope of the appended claims.

Having thus described my invention, I 100 claim:

1. A toy comprising an elevated spiral run-way, a drop column at the discharge end of said run-way, a gravity acting return run-way arranged with the intake end thereof at the bottom of the drop column and an 105

endless elevator to convey balls from the discharge end of the return run-way to the intake end of the spiral run-way.

2. A toy comprising an elevated spiral run-way, a drop column at the discharge end of said run-way, a gravity acting return run-way arranged with the intake end

thereof at the bottom of the drop column, an endless elevator to convey balls from the discharge end of the return run-way to the intake end of the spiral run-way, and a motor to operate the endless elevator.

In testimony whereof I affix my signature.

GEORGE B. BLILEY.
